UNITED STATES PATENT OFFICE.

CHARLES A. WESTBERG, OF CHICAGO, ILLINOIS.

SAFETY ATTACHMENT FOR ELEVATORS.

SPECIFICATION forming part of Letters Patent No. 339,035, dated March 30, 1886.

Application filed October 27, 1885. Serial No. 181,047. (No model.)

To all whom it may concern:

Be it known that I, CHARLES A. WESTBERG, a citizen of the United States of America, residing at Chicago, in the county of Cook and state of Illinois, have invented certain new and useful Improvements in Safety Attachments for Elevators, of which the following is a specification, reference being had therein to the accompanying drawings.

10 This invention has for its object to provide an elevator-shaft with horizontally sliding hatches—one for each floor—which hatches are to be opened automatically by the ascending and descending cage or platform, and to close again after such cage or platform has passed such floor, it being for the purpose of obviating accidents to persons and to prevent the rapid spreading of a fire in the building from one story to another.

15 My invention, therefore, consists of the novel devices and combinations of devices herein-after described and specifically claimed.

In the accompanying drawings, Figure 1 represents a longitudinal vertical section of a passenger or freight elevator having my attachments; Fig. 2, a transverse vertical section, and Fig. 3 a sectional plan, of the same.

Corresponding letters in the several figures of the drawings designate like parts.

20 A and B denote two of the several stories of the building; C, the elevator-shaft; D D', the guide-standards for the cage or platform E, that is suspended to hoist-rope F.

25 G G are two hatches that meet in the center of the elevator-shaft, where they are notched for clearing the hoist-rope F. These hatches are arranged to move in guide grooves or strips, and slide into or under the floor H simultaneously in opposite directions whenever the cage 30 or platform is passing such floor on its up or down course, such sliding movement being brought about by an automatic device actuated by the cage or platform itself as soon as it moves into close proximity above or below such 35 hatches, which I will now proceed to describe.

40 For my purpose the guide-standards D D' are grooved out from a short distance above floor H to an equal distance below such floor, and into each such groove I suspend on a link, a, 45 a bow-shaped bar, I, in a manner that its curved

back projects into the elevator-shaft, to be pushed into the groove of the standard by rollers b of the passing cage or platform E. Levers J are pivoted near their outer ends to brackets c, that are rigid with standards D D', and the outer extremities of these levers J are pivotally connected with the ends of bars I, each by a link, d. The opposite ends of both levers J of each standard D nearly meet within the floor H, where a very short lateral movement of 55 the bar I will impart to these lever ends an increased swinging motion, which motion of all levers J will be simultaneous.

50 Behind each standard D or D', and under floor H, are pivotally secured two bell-crank, 60 L L', on a sufficiently-different elevation to clear each other, and the short arm of each such bell-crank is in contact with the end of one of the levers J, in a manner that the swinging of such lever will be imparted to such 65 bell-crank, causing the long arm of the same to swing a proportionally-increased distance, as clearly shown by dotted lines in Fig. 3. A rope or cord, f, secured by any suitable means to the end of the long arm of each bell-crank 70 L, is passed around a pulley, M, and its opposite end is secured to one corner of one of the two hatches G in a manner that each such hatch is thus connected with one of the bell-cranks 75 of each standard D and D'. The opposite or 80 inward corners of the hatches G have ropes g attached, each of which is passed over a pulley, h, and has suspended to its end a sash-weight, N, that moves in a vertical box, O, built against the side of the standard D D'. 85 The sash-weights N, by their gravity, will hold the hatches closed; but as soon as the cage or platform is moving into close proximity with such hatches the rollers b of such cage or platform will be brought into contact with the bow-shaped bars I, and by degrees will force them apart, thereby actuating the levers J and bell-cranks L, which, by their rope connection, will 90 pull the hatches sufficiently apart to allow the cage or platform to pass, whereby the sash- 95 weights N are elevated, and as soon as the cage or platform releases the bars I the weights N by their gravity will move the hatches again toward each other, and will thus close the elevator-shaft. This device being applied to each 100

floor, accidents, now so frequently occurring, are obviated, and in case a fire should break out on either floor it is checked from rapid spreading into the other floors of the building.

5. What I claim is—

1. The combination, in an elevator attachment, with sliding hatches and bow-shaped bars suspended in the guide-standards, of suitable levers intermediate the bars and hatches, as and for the purposes set forth.
2. The combination, in an elevator attachment, with sliding hatches and bow-shaped bars suspended in the guide-standards, of suitable levers intermediate the bars and hatches and counterbalancing weights connected to the hatches, as set forth.

15. 3. The combination, in an elevator attachment, with sliding hatches G G', of bars I, suspended from links a, levers J, pivoted to bars I by links d, bell-cranks L, and cords f, as set forth.

4. The combination, in an elevator attachment, with sliding hatches G G', of bars I, suspended from links a, levers J, pivoted to bars I by links d, bell-cranks L, cords f, and weights N, as set forth.

In testimony whereof I affix my signature in presence of two witnesses.

CHARLES A. WESTBERG.

Witnesses:

RICHARD REINBOLD,
FRANK S. BLANCHARD.
